UNITED STATES PATENT OFFICE.

THOMAS C. SHEEHAN, OF ESSEX FELLS, NEW JERSEY, ASSIGNOR, BY MESNE ASSIGNMENTS, TO AMERICAN HIGH SPEED PRESS COMPANY, OF NEW YORK, N. Y., A CORPORATION OF NEW YORK.

STRIPPER-OPERATING MECHANISM.

1,123,022.

Specification of Letters Patent. Patented Dec. 29, 1914.

Original application filed August 29, 1906, Serial No. 332,470. Divided and this application filed January 27, 1914. Serial No. 814,671.

To all whom it may concern:

Be it known that I, THOMAS C. SHEEHAN, a citizen of the United States, residing at Essex Fells, in the county of Essex and State of New Jersey, have invented a new and useful Stripper-Operating Mechanism, of which the following is a specification.

This is a division of my application Serial No. 332,470 filed August 29, 1906, for a printing machine, and the invention relates particularly to that class of job printing machines known as "self-feeding automatic platen presses" and especially to the frisket gripper thereof.

The principal object of the present invention is to provide an improved stripper operating mechanism consisting of a small number of parts which will hold the sheet of paper taut against the platen just before the printing operation takes place; will keep the printed sheet of paper from sticking to the type or form when the form moves away from the printed sheet; and in which the stripper fingers will then open to permit the regular grippers to advance the sheet of paper to the delivery table, and operating so that the strippers will be given their necessary motions in a smooth and easy manner.

Reference is to be had to the accompanying drawings, in which a preferred embodiment of the invention is shown and in which—

Figure 1 is a view of a portion of such a press, looking toward the platen, in elevation and showing a portion of the gripper mechanism in connection with the stripper mechanism; and Figs. 2 and 3 are side views of the same showing the press in open and closed positions respectively.

The reference numeral 1 indicates the side frames of the machine for suitably supporting the component parts thereof, including the platen 87. The bed 5 which carries the inking mechanism is of well known construction and only the outline is shown, the inking mechanism not being indicated. This is pivoted in the frame at 6 as usual, and oscillates in the well known manner through the instrumentality of a link 7, the connections for operating which are not illustrated. Between the side frames and adjacent to the feed, not shown, is located the registering table 20. The sheets are fed over this table

in any well known manner, the various devices for registering the sheets and placing the same in the position for the grippers being employed as usual. Tapes 24 which pass over the surface of the registering table are indicated for carrying the sheets forward from the feed. Then they are side registered, and brought to the gripper mechanism which forms the subject matter of my companion application thereon filed on even date herewith, Serial No. 814,672. Therefore the said gripper mechanism is not described in full but it is mounted between two carriages 71, which are pivoted at 72 to a collar 73, fast on reciprocating rods 74 one on either side of the machine. The said rods travel in suitable bearings 75, on the side frame, and motion is imparted to them by means of a bell crank 76, pivoted on the frame at 77, and connected to the said rods by means of a link 78. A spring 79 pushes on the short arm of the said bell crank, and tends to move the guide rods and the gripper mechanism carried thereon downwardly. A further means for effecting this downward motion is found in a rod 80, pivoted on the bed at 81, and pulling against a projection 82 on the bell crank 76. This pull is made yieldingly by means of a spring 83. The upward motion of the guide rod and gripping mechanism is caused by the rocking of the bed, which pushes the short arm 85 of the bell crank 76 down, hence moving the guide rods up. In order to prevent jars or blows by the engagement of the bed with the said bell crank, the latter is provided with friction rolls 84 (only one of which is seen). 90 A cam 85 is connected with the inking mechanism and moves with the inking rollers (not shown), and as the bed rocks away from the platen, the said cam engages one of the rollers 84 in a smooth and easy fashion, thus starting the downward motion of the bell crank. Next a hub 86 on the bed engages the other roll 84, before the cam 85 leaves the first roll in order to rock the bell crank positively and move the grippers up, 95 but this engagement of the hub with the bell crank takes place without any blow inasmuch as the bell crank has been started on its motion by the cam 85. The operation of these parts is clearly shown in Figs. 2 and 3. 100 105

The gripper mechanism travels in a

straight line up and down over the surface of the platen 87.

The stripping means shown comprises two flat pieces, 117, mounted on an oscillating shaft 118 on the frame, having an arm 116 thereon. This shaft is operated in opposition to spring 118^a by means of a roll 119 on the arm 116, engaging a track 120, which is carried by and reciprocates with the grip-
10 per carriage 71. As will be seen from Figs. 2 and 3, the roll 119 runs on the low part of the track 120 when the press is open, and the strippers afford no obstruction to the downward travel of the sheet. In Fig. 3 the roll 15 is on the high part of the track, and the strippers are closed against the platen, and while in this position, a roll 121, carried by the bed, acts on a cam surface 122 on the arm 116 to positively hold the strippers in 20 their position. Thus it will be seen that the reciprocable sheet gripping device is yieldingly actuated by the springs 79 and 83 to operate the stripper throughout most of the action thereof but the bed positively oper- 25 ates the strippers toward the platen and holds them in position on the platen when the bed is in printing position.

While I have illustrated and described a preferred form in which my invention may 30 be embodied, and while I have shown it as it may be constructed when used in connection with a particular type of printing machine, I am aware that many modifications 35 may be made therein, and that the invention can be adapted for use with other types of printing machines by any person skilled in the art without departing from the scope of the invention as expressed in the claims. Therefore, I do not wish to be limited to the 40 particular construction shown and described, but

What I do claim is:—

1. In a printing machine, the combination of a bed, a stripper, means to initially advance the stripper to operative position, and separate means carried by the bed for positively holding the stripper in position on the platen when the bed is in printing position.

Copies of this patent may be obtained for five cents each, by addressing the "Commissioner of Patents, Washington, D. C."

2. In a printing machine, the combination of a bed, pivoted strippers located adjacent 50 to the platen of the machine, yieldingly operated devices for initially positioning the strippers close against the platen, and means on the bed for positively forcing the strippers toward the platen. 55

3. In a printing machine, the combination of a stationary platen, a movable bed, a pin mounted on said bed, a pair of pivoted strippers mounted adjacent to the platen, means for swinging the strippers toward the 60 platen, and a cam connected with said strippers for engaging said pin and positively forcing the strippers against the platen.

4. In a printing machine, the combination 65 of a platen, strippers located adjacent thereto, a movable carriage for carrying a gripping mechanism, a device for operating the strippers comprising a lever having a roll, and a track having an offset portion mov- 70 able with said carriage for engaging said roll to operate the strippers.

5. In a printing machine, the combination of a stripping device, a bed, a movable sheet gripping device, means operated by 75 the gripping device for operating the stripping device, and means on the bed for positively operating the stripping device.

6. In a printing machine, in combination, a bed, a platen, a stripper, means to preliminarily position said stripper in operative relation to said platen as the bed commences its movement, and additional means for thereafter positively holding said stripper against said platen, said additional 85 means becoming operative as the bed completes its movement to printing position.

In testimony whereof I have hereunto set my hand, in the presence of two subscribing witnesses.

THOMAS C. SHEEHAN.
